UNITED STATES PATENT OFFICE.

BERNARD PALAZOT, OF BORDEAUX, FRANCE.

IMPROVEMENT IN FURNACES.

Specification forming part of Letters Patent No. **39,168**, dated July 7, 1863.

To all whom it may concern:

Be it known that I, BERNARD PALAZOT, of Bordeaux, in the Empire of France, engineer, have invented a new and useful Improvement in Smoke-Consuming Furnaces; and I do hereby declare that the following is a full, clear, and exact description of the construction and operation of the same, reference being had to the annexed drawings, making part of this specification, and to the letters marked thereon.

My invention consists in an improved arrangement of certain parts of steam-boiler and other furnaces, by means of which perfect combustion and complete fumiority are obtained, accompanied in many cases by a considerable economy of fuel.

The annexed drawings represent in cross and longitudinal section a boiler-furnace comprising the present improvements.

A is a slit aperture formed across the furnace in front of the grate and giving passage to a current of air, the volume and velocity of which are regulated by the register B.

C is a vaulting of refractory clay, which in certain cases may be replaced by a simple plate. The form of this vault or plate may be modified,

so long as its position above the fire bridge be retained, as seen in the drawing, so as to concentrate the heat at the passage of the flame in D D. The section of this passage D D should be about one-fifth or one-sixth of the surface of the grate.

On opening the register B of the furnace, arranged as above, the atmospheric air is admitted, and, flowing over the incandescent surface of the fuel, mingles with the gaseous products of the combustion, which, being thus oxygenised, are entirely consumed in their passage under the vaulting.

Having now described the nature of my said invention, I declare that I claim—

The improved combination of the vaulting or plate C, with the air entry A and register B, applied to boiler and other furnaces, the whole constructed and arranged in manner and for the purpose substantially as herein specified, and shown in the figures of the annexed drawings.

BERNARD PALAZOT.
